United States Patent

Des. 240,046
Patented May 25, 1976

240,046

SOLAR CELL OR SIMILAR ARTICLE

Joseph Lindmayer, Bethesda, Md., assignor to
Solarex Corporation, Rockville, Md.

Filed Oct. 23, 1973, Ser. No. 409,008

Term of patent 14 years

Int. Cl. D13—02

U.S. Cl. D26—1 R

The sole figure is a top plan view of a solar cell or similar article showing my new design.

The solar cell is of no substantial thickness and the rear is flat and plain.

I claim:

The ornamental design for a solar cell or similar article, as shown.
